Application May 11, 1945, Serial No. 593,153

14 Claims. (Cl. 178—7.2)

1 The present invention relates to a method and means for controlling the scanning beam intensity in a television camera tube.

In particular, the invention will be found to be applicable to camera tubes of the so-called low-velocity scanning beam types. A tube known as the "Orthicon" is thus one of the types with which this invention finds particular use. The "Orthicon" type camera tube is known, *per se*, in the art, and details concerning its construction and general operation may be had by reference to the article entitled "The Orthicon, a television pick-up tube," by Messrs. Rose and Iams which was published in the "RCA Review" for October, 1939, and which appeared, with certain bibliography, in pages 186 to 199 inclusive.

The storage-type pickup tube known as the "Orthicon" differs from other camera tubes used in television transmitting systems in the use of a low-velocity beam of electrons for scanning the mosaic. In an "Iconoscope," for example, the cathode ray scanning beam impacts the mosaic element at high velocity, and has the effect of exciting secondary emission from the mosaic surface. Variations in the number of these secondary electrons which are collected constitute the video signal output, as is already understood in the art.

While both of the above types of tube include a mosaic element on which there is set up an image in the form of stored electrostatic charges, the principle of operation of the "Orthicon" is such that the electrons in the low-velocity scanning beam may be collected from the beam as it passes over the elemental areas of the mosaic surface and employed to neutralize the positive charges existing on these areas. The number of scanning beam electrons collected at any instant will depend on the magnitude of the negative charge deficiency possessed by the particular surface area being instantaneously scanned by the cathode ray scanning beam, and this negative charge deficiency, in turn, is proportional to the brilliance of the homologously associated point on the optical image to be transmitted.

Thus, the positive charges on the mosaic, which represent an electrostatic image corresponding point-for-point to the optical image, are neutralized by the scanning beam electrons. Due to the differences in magnitude of the positive charges acquired by the various elemental areas of the mosaic surface, the total number of electrons present in the scanning beam is not always required to neutralize a particular mosaic area. The "excess" beam electrons or, in

2 other words, those not collected by the mosaic, are returned toward the electron gun end of the camera tube.

In one species of the proposed "Orthicon" camera tube, the video signal output is derived directly from the mosaic as a result of variations in the number of scanning beam electrons which are collected thereby. In another species, those electrons remaining in the beam after the electrons therein required for neutralization have been collected by the mosaic are returned to an electron-collecting electrode adjacent the electron gun and there collected to produce the signal current. In the latter arrangement, the signal output current of the camera tube is equal to the original beam current as produced by the electron gun less the number of electrons lost by the beam to neutralize the positive charges as it scans each point of the mosaic so that the quantity of electrons lost in this manner is proportional to the density of the electron image on that particular mosaic portion and hence the brilliance of the corresponding point on the optical image. Accordingly, the electron beam from the gun of the camera tube is modulated by the mosaic potentials in accordance with the characteristics of the optical image to be televised, and the modulated electron beam utilized as the video signal output of the tube.

30 The number of electrons instantaneously collected from the scanning beam is controlled by the potential of the mosaic at the point of instantaneous scanning of the mosaic by the scanning cathode ray beam or, as above stated, on the negative charge deficiency of that elemental mosaic area. If such charge deficiency is zero, as a result of zero illumination being received from the corresponding point on the optical image, then approximately all of the electrons present in the scanning beam at that instant will be returned toward the electron gun. The number of electrons so returned will be approximately equal to the number originally emitted, or in other words the returned electrons will approximately equal in value the beam current of the tube. Returned electrons approximately equal in number to those in the emitted scanning beam when collected constitute one limit of video signal current.

40 At the other extreme is the condition when substantially none of the electrons emitted from the gun is returned from the mosaic. This occurs when substantially all of the electrons present in the scanning beam are required to make up the negative charge deficiency on a particular

mosaic area due to the extreme brightness of the corresponding or homologous point on the optical image. The zero current thus produced in the output circuit constitutes the other video signal limit.

It will be clear from the above description that under the ideal conditions set forth the emitted scanning beam is modulated between the limits of zero and 100%. It will be further appreciated that to produce 100% modulation substantially all of the scanning electrons must be collected by the mosaic and none allowed to return toward the electron gun end of the camera tube. Inasmuch as the number of electrons in the scanning beam at any instant is normally substantially constant, it is obvious that there is only one value of negative charge deficiency at which any particular elemental mosaic area will collect substantially all of the electrons present in the scanning beam and be completely neutralized thereby. This value of negative charge deficiency at which substantially all of the electrons in the scanning beam are collected to produce complete neutralization represents the maximum value of brightness permissible at any one point on the optical image without introducing distortion into the output of the camera tube.

The above statement will be appreciated when it is considered that an increase in brightness beyond the maximum value mentioned will increase the negative charge deficiency on the mosaic element under consideration to a point where there are insufficient electrons present in the scanning beam to make up the deficiency. Distortion of the televised image accordingly results.

Since undermodulation of the scanning beam of a low scanning beam velocity camera tube is undesirable, the beam current is usually set so that 100% modulation will result at the maximum brightness level anticipated for the particular object to be televised. It often happens, however, that for various reasons the maximum brightness of the object exceeds this anticipated level, necessitating manual adjustment of the value of the beam current. On the other hand, should the maximum brightness of the object be below the anticipated level, the noise-to-signal ratio in the output is increased unless manual adjustment is made.

In my copending U. S. patent application Serial No. 572,009, filed January 9, 1945, I have disclosed a method and means for maintaining the beam current in a low scanning beam velocity television camera tube of the type having a separate photocathode fully modulated regardless of variations in the illumination, thereby producing a uniformly clean and powerful signal with a minimum of shading and, in addition, eliminating the noise due to an unnecessarily high beam current under low light conditions. As shown in this copending application, the above is accomplished by utilizing the secondary electrons emitted when the electron image produced by the photocathode of the tube impinges on the mosaic. Since the number of secondary electrons so emitted is proportional to the average strength of the overall illumination on the photocathode, these secondary electrons are collected and caused to produce a voltage which is applied to the control electrode of the camera tube gun so as to vary the beam current of the tube in such a manner that the beam current is of a value just sufficient to discharge the mosaic under the light conditions then prevailing.

The present invention features a method and

means for utilizing a portion of the video signal output of the camera tube to accomplish the same objectives, thus eliminating the necessity of employing a separate circuit for collecting and storing the secondary electrons emitted from the mosaic by the impingement thereon of the electron image produced by the photocathode. Furthermore, since the present invention does not require the presence of secondary electrons to create a compensating control variation, the system disclosed herein is not restricted to a camera tube of the type having a separate photocathode. Instead, a camera tube may be employed in which an object to be televised is focused directly on a so-called double mosaic which, if desired, may be of the type disclosed by L. E. Flory in U. S. Patent No. 2,045,984, granted June 30, 1936, or, if the mosaic is semi-transparent, of the type shown in Patent No. 2,150,980, issued March 21, 1939, to H. G. Lubszynski et al.

One object of the present invention, therefore, is to provide a method and means for automatically controlling the grid bias in a television camera tube.

Another object of the invention is to provide a method and means for maintaining a substantially 100% modulated beam current for a low-velocity scanning beam type television camera tube regardless of variations in the average overall illumination received from the object being televised.

A further object of the invention is to provide a method and means for utilizing a portion of the video signal output of a low scanning beam velocity type television camera tube so as to control the beam intensity of the tube.

Other objects and advantages will be apparent from the following description of preferred forms of the invention and from the drawing, in which:

Fig. 1 illustrates schematically a preferred form of circuit incorporating the present invention;

Fig. 2 is a curve which is referred to in explaining the operation of the circuit of Fig. 1; and

Figs. 3, 4, 5, and 6 are circuit diagrams showing alternative arrangements in accordance with the present invention.

Referring first to Fig. 1, there is shown a television pickup or camera tube 10. The elements of tube 10 for producing an electrostatic image are of the character referred to in my above-mentioned copending U. S. patent application, Serial No. 572,009. These elements hence are not herein to be described in detail, but they will be understood to include a photocathode 12 on which an image of an object 14 is focused by means of a lens 16. Photocathode 12 is connected to the negative terminal of a battery 18 or other source of potential. Illumination falling on photocathode 12 causes an emission of electrons from the inner surface thereof, such emission, as is well known in the art, being in the form of an electron image each point of which corresponds in density to the strength of the illumination on the corresponding point of photocathode 12.

The velocity of the electrons thus emitted from the surface of photocathode 12 is increased by an accelerating electrode 20 which is shown as an annular band of metal on the wall of tube 10 but which may be of any other suitable type, and which is connected to an intermediate point on battery 18, toward a mosaic electrode 22 which is connected to the positive terminal of battery 18.

While mosaic 22 is preferably composed of semi-conducting material as set forth in a co-

pending U. S. patent application of Albert Rose, filed September 20, 1940, as Serial No. 357,543, now abandoned, it may, if desired, be of the so-called double-mosaic type as disclosed by Flory Patent No. 2,045,984, above mentioned. The photocathode structure 12 may readily be formed as disclosed by Patent No. 2,248,977, granted to Flory et al. on July 15, 1941. A suitable electron lens (not shown) which may, for example, be of the type disclosed in the mentioned Flory et al. Patent No. 2,248,977, or in Patent No. 2,189,319, issued February 6, 1940, to G. A. Morton, is employed to focus on the mosaic electrode 22 the electrons emitted from the surface of photocathode 12.

Electrons impacting the mosaic 22, in turn, cause secondary electrons to be released therefrom, these secondary electrons being collected by a screen 24. The release of secondary electrons by a particular element or area of mosaic 22 leaves such element with a positive charge or, in other words, with a negative charge deficiency. The amount of such actual deficiency is dependent upon the density of the electron image at that particular point.

The positively charged mosaic 22 is then scanned by means of an electron beam produced by an electron gun at the opposite end of tube 10, this electron gun being of any suitable type which includes a cathode 26, a grid 28 and an accelerating anode (not shown). The beam deflecting means of tube 10 is conventional and might be magnetic, electrostatic or a combination. One preferred form may be considered as being of the form disclosed by the aforementioned U. S. patent application of Albert Rose, Serial No. 357,543. The deflecting electrode system is consequently omitted from the drawing for the sake of clarity and simplicity of illustration.

As the scanning beam travels across the surface of mosaic 22, electrons from the beam neutralize the positively charged mosaic elements. The beam normally supplies sufficient electrons to make up the negative charge deficiency of each image point or element. If a particular element is not positively charged, or if such positive charge is small enough so that all of the electrons available in the scanning beam during the instant of passage are not required to make up the negative charge deficiency on that element, then the remaining electrons in the beam or, in other words, those not employed to neutralize the electrostatic charge representing each image point or element, are caused to return along a path substantially parallel with the scanning beam toward the end of tube 10 from which they are emitted. Upon arriving at the end of tube 10 containing the electron gun, these returned electrons are collected by a signal plate 30 forming a part of the tube output circuit. Signal plate 30 may be of any suitable design, such for example, as a circular disk having a central aperture through which the scanning beam electrons emitted from cathode 26 may pass.

The signal output of tube 10 is amplified, if desirable or necessary, by two video amplifiers 34 and 36. In accordance with the present invention, a portion of the signal output energy of tube 10 is utilized to provide a control variation for the electron scanning beam of the camera tube in a manner now to be described.

In the circuit shown in Fig. 1, the top plate (in the drawing) of a condenser 38 is connected between the two video amplifiers 34 and 36. The other plate of condenser 38 is connected to ground through a resistor 40. Shunted across resistor

40 is a diode 42 having its cathode connected to ground. A second diode 44 has its cathode connected to the anode of diode 42. The anode of diode 44 is connected to ground through a resistor 46 in parallel with a condenser 48. Diodes 42 and 44 may, if desired, comprise the two sections of a tube of the general type known as the 6H6.

In the waveform 49 of Fig. 2, which is the waveform of a signal such as might be present in the output of amplifier 34, the video signal variations are of such polarity as to extend in a negative direction to a certain maximum amplitude during each line-scanning interval, this maximum amplitude being indicated by the reference character 50. Extending in the opposite, or positive, direction from the A.-C. axis 52 of the signal, are blanking pulses 54 formed by the application of a series of blanking pulses 56 (Fig. 1) from a suitable source (not shown) to screen 24 of tube 10 over conductor 58.

A portion of the signal output of video amplifier 34, such, for example, as represented by the waveform 49, is applied to the diodes 42 and 44 through condenser 38. When a positive portion of wave 49, such as one of the blanking pulses 54, reaches diodes 42 and 44, the former will be rendered conductive to charge condenser 38 by an amount determined by the height of the top of the positive pulse 54 above the A.-C. axis 52.

During the conduction of diode 42, both point 56 and the cathode of diode 44 are at D.-C. ground potential. When now a negative portion of wave 49 reaches diodes 42 and 44, diode 44 will be rendered conductive to develop across the resistor-condenser combination 46, 48 in the anode circuit of diode 44 a voltage which is equal to the amplitude of the most negative point 50 of wave 49 taken with respect to D.-C. ground. Since this D.-C. ground level, as described above, has been set at the top of blanking pulse 54, the voltage across condenser 48 will be that developed between point 50 and the top of pulse 54 or, in other words, will be the peak-to-peak voltage of the signal wave 49.

When the illumination received by photocathode 12 from any point on object 14 increases, the corresponding element of mosaic 22 becomes more positive. This results in a decrease in the number of electrons collected by the signal plate 30 as the electron beam scans that particular mosaic element, and as a result the most positive and negative points on the signal output curve, as, for example, the point 50 and the top of pulse 54 on the illustrative waveworm 49, move further apart. This increase in peak-to-peak signal voltage increases proportionally the charge on condenser 48.

The time constant of resistor 46 and condenser 48 is chosen to give a satisfactory D.-C. variation with respect to changes in illumination, being preferably in the order of the time required to scan several frames. In any event, such time constant should not be less than one line-scanning interval, as otherwise instantaneous A.-C. variations will result which are objectionable for reasons which will later become apparent.

The voltage developed on condenser 48 is applied to the control grid 58 of a tube 60 which is designed to act as a D.-C. amplifier. Inasmuch as the voltage developed on condenser 48 is negative with respect to ground, an increase in the voltage on condenser 48 in response to an increase in the peak-to-peak signal voltage output of camera tube 10 places a more negative bias on the control grid 58 of tube 60. This reduces

the plate current of tube 60 and causes the plate end of load resistor 62 to become more positive. This decreased potential drop across resistor 62 is applied, by means to be hereinafter described, as a decrease in negative bias on the control grid 28 of camera tube 10 to increase the intensity of the beam current of tube 10 to a point where it is just sufficient to neutralize the charges on mosaic 22 under the increased illumination conditions and thus prevent overmodulation of the scanning beam.

Since tube 60 is designed for substantially linear operation, variations in the negative charge on condenser 48 will produce substantially proportional variations in the positive voltage appearing on the plate end of load resistor 62.

To obtain a control voltage for the grid 28 of camera tube 10 which is of correct polarity, the positive voltage appearing on the plate end of load resistor 62 is bucked out with a negative voltage from a source of potential (not shown) connected to the terminal 64, this latter source being of such value as to produce a negative voltage at point 66 which varies in substantially inverse proportion to the changes in positive potential appearing on the plate end of load resistor 62.

The circuit of Fig. 3 is essentially the same as that of Fig. 1 with the exception that two video amplifiers 68 and 70 have been added and the D.-C. amplifier tube 60 and its associated elements omitted. Whereas in Fig. 1 the resistor-condenser combination 46, 48 was connected in the anode circuit of diode 44 to produce a negative charge on condenser 48, in Fig. 3 the same resistance-condenser combination is connected in the cathode circuit of diode 42 to produce a positive charge on condenser 48. The varying positive charge produced on condenser 48 during operation of the system causes variations in the negative D.-C. bias placed on grid 28 of camera tube 10 by a battery or other source of potential 72 through resistor 46.

While the systems of Figs. 1 and 3 are satisfactory for many operations, they do not have the same stability as the circuit of Fig. 4 (later to be described), due to the fact that they are regenerative. If the bias on the camera tube 10 is accidentally set too positive, the scanning beam current is caused to reach an unnecessarily high level. The excessively large number of electrons present in the scanning beam tends to produce a condition known as "shading," which has the same effect, insofar as the output of the camera tube is concerned, as an increase in the amount of illumination falling upon the photocathode. Consequently the output of the camera tube increases, which in turn causes a still further increase in the scanning beam current.

In Fig. 4 is shown a system whereby the regenerative operation of the circuits of Figs. 1 and 3 is overcome by the utilization of a limiter tube 74 connected across the condenser 48. Whenever the positive voltage on condenser 48 increases to a point where it exceeds a predetermined maximum value as determined by the potential of battery 76, diode 74 is rendered conductive. The voltage developed on condenser 48 is thus prevented from reaching a point sufficiently high to cause objectionable regeneration.

In Fig. 5 is shown means whereby an automatic video gain control may be added to the system of Fig. 4. This is accomplished by utilizing a parallel resistor-condenser combination 78, 80 in the anode circuit of diode 44. A negative voltage on condenser 80 will be developed

during operation of the system of Fig. 5 in the same manner that a negative voltage is developed on condenser 48 in the system of Fig. 1.

If the signal from camera tube 10 increases, for example, there is need for more scanning beam current and less video gain. In Fig. 5 the voltage on condenser 48 will become more positive due to the increase in peak-to-peak signal voltage as hereinabove brought out, and this increase in voltage on condenser 48 is applied to grid 28 of camera tube 10, as in Fig. 4, to increase the scanning beam current. The voltage on condenser 80, however, will become more negative, and this increase in negative voltage on condenser 80 is applied over a conductor 82 to reduce the gain of the video amplifier 36 in any suitable manner, such as by increasing its negative bias.

The system of Fig. 6 is similar to that of Fig. 5, except that the gain control voltage is applied to the signal circuit not only over conductor 82 after a portion of the signal has been detected by diodes 42 and 44, but also over a conductor 84 before the signal is detected. This tends to stabilize the system because it effectively reduces the gain of the rectifier circuit. If the voltage on condenser 48 exceeds a predetermined maximum value, diode 74 is rendered conductive, thereby placing all of the voltage that would appear on condenser 48 across condenser 80. This increased negative charge on condenser 80 is applied over conductors 82 and 84 to reduce the amplitude of the signal and restore the normal operating status of the system.

If desired, the limiter tube 74 and battery 76 may be omitted from the circuit of Fig. 6. Such an omission, however, tends for increased instability and possibly excessive regeneration.

Other modifications, of course, will be obvious to those skilled in the art to which the invention is directed.

Having now described the invention, what is claimed and desired to be secured by Letters Patent is the following:

1. In a television system, a camera tube of the type in which a mosaic electrode within said tube is adapted to be scanned by a low-velocity scanning beam to thereby develop an output signal, an amplifier for the output signal of said tube, means for peak-to-peak rectifying a portion of the signal, means for applying a portion of the rectified energy to control the intensity of the scanning beam of said tube in direct proportion to said signal, and means for applying at least a portion of the remaining rectified energy to control the degree of amplification of said signal in inverse proportion thereto.

2. In a television system, a camera tube in which a cathode ray scanning beam is developed to scan a mosaic electrode on which electrostatic charges are developed in proportion to the brilliancy of an optical image, the signal output of said tube having a peak-to-peak value which is a measure of the brilliancy of said optical image, a peak-to-peak rectifier, means for applying the signal output of said camera tube to said peak-to-peak rectifier, an energy storage circuit, means for applying the output of said peak-to-peak rectifier to said energy storage circuit so as to develop a relatively smooth D.-C. having an amplitude approximately equal to the peak-to-peak value of the signal output of said camera tube, and means for applying the output of said energy storage circuit to said camera

tube to control the intensity of said scanning beam in direct proportion to said peak-to-peak value of the signal output.

3. A television system in accordance with claim 2, in which the said energy-storage circuit comprises a resistance-condenser combination having a time constant equal at least to the time required for the said scanning beam to make one complete scansion of the said mosaic electrode.

4. In a television system, a camera tube of the type in which a mosaic electrode within said tube is adapted to be scanned by a low-velocity scanning beam to thereby develop output signals, a pair of video amplifiers in the output circuit of said camera tube, a pair of diodes, means for applying a portion of the signal output of said camera tube appearing between said video amplifiers to the anode of one of said diodes and to the cathode of the other of said diodes, means connecting the cathode of said one diode to ground, a parallel resistor-condenser combination, means connecting the anode of said other diode to ground through said parallel resistor-condenser combination, and means for applying the charge developed on said condenser during operation of the system to control the intensity of said scanning beam.

5. The combination of claim 4 in which said last-mentioned means includes a D.-C. amplifier, the charge developed on said condenser being applied to control the operation of said D.-C. amplifier.

6. The combination of claim 2, further comprising means for limiting approximately a predetermined value the energy stored by said energy-storage circuit.

7. The combination of claim 2, further comprising means for limiting to approximately a predetermined value the energy stored by said energy-storage circuit, said limiting means comprising a diode and a source of potential connected in series across said energy-storage circuit, the positive terminal of said potential source being connected to the cathode of said diode and the anode of said diode being connected to the positive output terminal of said energy-storage circuit.

8. In a television system, a camera tube of the type having a mosaic electrode, and wherein a low-velocity scanning beam is developed and deflected to scan said mosaic electrode to thereby produce output signals, means for amplifying the signal output of said camera tube, a pair of diodes, means for applying a portion of the signal output of said camera tube to the anode of one of said diodes and to the cathode of the other of said diodes, a first energy-storage circuit connected between the cathode of said one diode and ground, a second energy-storage circuit connected between the anode of said other diode and ground, means for applying the output of said first energy-storage circuit to control the intensity of said scanning beam, and means for applying the output of said second energy-storage circuit to control said amplifying means.

9. In a television system, a camera tube of the type wherein a cathode-ray scanning beam is developed and then deflected to scan a mosaic electrode in said tube to produce output signals, a first amplifier and a second amplifier connected in cascade, means for applying the signal output of said camera tube to said first amplifier, a pair of diodes, means for applying a portion of the sig-

nal output of said first amplifier to the anode of one of said diodes and to the cathode of the other of said diodes, a first energy-storage circuit connected between the cathode of said one diode and ground, a second energy-storage circuit connected between the anode of said other diode and ground, means for applying the output of said first energy-storage circuit to control the intensity of said scanning beam, and means for applying the output of said second energy-storage circuit to control the gain of both said first and second amplifiers.

10. In a television system having a camera tube of the low-velocity scanning-beam type, the method for automatically adjusting the electron beam current to light intensities which comprises, deriving from said tube a picture signal representing a succession of instantaneous values of light received by said tube, rectifying a portion of said picture signal and deriving therefrom a unidirectional signal proportional to the peak-to-peak amplitude of said picture signal, averaging said unidirectional signal over a plurality of scanned fields, and using said averaged unidirectional signal to control the electron beam current in direct proportion to said averaged unidirectional signal.

11. The method according to claim 10 including the steps of amplifying said picture signal and using said averaged unidirectional signal to control the amplification in inverse proportion to said averaged unidirectional signal.

12. The method according to claim 10 including the steps of amplifying said picture signal both before and after performing said rectifying step, and using said averaged unidirectional signal to control both amplifications in inverse proportion to said averaged unidirectional signal.

13. In a television system, a camera tube of the low-velocity scanning-beam type, said tube containing means for controlling the electron current of the beam and means providing a picture-signal output, means for rectifying a portion of said output and deriving therefrom a unidirectional potential proportional to the peak-to-peak amplitude of said output, means for averaging said unidirectional potential over a plurality of scanned fields, and means for applying said averaged unidirectional potential to said beam control means in a direction to vary the electron current in direct proportion to said peak-to-peak amplitude.

14. The combination defined by claim 13 wherein said applying means comprises means for placing an upper limit upon the unidirectional potential applied to said beam control means.

ROBERT R. THALNER.
